UNITED STATES PATENT OFFICE.

FRANK A. CORTIS, OF MERIDEN, CONNECTICUT, ASSIGNOR OF ONE-HALF
TO DWIGHT T. CORTIS, OF BOSTON, MASSACHUSETTS.

LAMP.

SPECIFICATION forming part of Letters Patent No. 613,648, dated November 1, 1898.

Application filed March 20, 1896. Serial No. 584,109. (No model.)

To all whom it may concern:

Be it known that I, FRANK A. CORTIS, a citizen of the United States, and a resident of Meriden, in the county of New Haven and 5 State of Connecticut, have invented certain new and useful Improvements in Lamps, of which the following is a full, clear, and exact description, whereby any one skilled in the art can make and use the same.

10 My invention relates particularly to the class of so-called "lamps" which are used in the Welsbach system, where a mantle or veil of extremely fragile material is used, this mantle being brought to a high state of incandescence to provide the luminous body in the lamp. In lamps of this construction, owing to the fragile nature of this mantle, a jar or shock comparatively light in degree will cause the mantle, which is supported from 15 near its upper edge, to break, and thus destroy the lamp as to its most essential feature.

The object of my invention is to provide means whereby the mantle-supporting portion of the lamp may be insulated from shocks 20 and jars; and to this end it consists in the combination, with the lamp-support, of a yielding cushion interposed between the lamp-support and the mantle-support, and in details 25 of the several parts making up the device as 30 a whole, and in the combination of such parts, as more particularly hereinafter described, and pointed out in the claims.

Referring to the drawings, Figure 1 is a view 35 in side elevation of a lamp embodying my improvement with parts cut away to show construction. Fig. 2 is a detail view, on enlarged scale, showing the cushion. Fig. 3 is a detail view, on enlarged scale, showing a modified form of cushion and its arrangement. 40 Fig. 4 is a detail top or plan view of the air-shutter and spring-cushion.

In the accompanying drawings my invention 45 is illustrated in connection with a single lamp of the kind described, and the letter *a* denotes a gas-bracket on which the lamp as a whole is supported. A feature of this form 50 of lamp includes means for controlling the quantity of air which may be allowed to unite with the illuminating-gas before the latter is ignited at the upper end of the burner, and

this device, known as the "shutter," is denoted by the letter *b*. This air-shutter *b* is a hollow device, usually of thin metal, as brass, with air-ports through the lower part adapted to be closed to a greater or less degree by 55 means of a sliding damper, and there is sufficient space within the body of this device and outside the central tube *c*, in which the air and gas are mixed, to permit the spring of an elastic cushion *e* to be arranged. 60

Prior to my invention the chimney-gallery *f* (which supports the chimney *g*, a mantle *h*, and in most instances a shade) has been supported directly on top of the air-shutter, the mixing or central tube *c* extending through 65 a central opening in the chimney-gallery, as shown in dotted line in Fig. 1, which gallery is thus supported firmly in an upright position. When the parts are so supported, any jar given to the gas-bracket or other support for 70 the lamp or the lamp itself is communicated directly to the chimney-gallery and mantle-support and causes the mantle to break short off at the neck or upper portion, and thus become destroyed. In order to avoid this, a spring⁷⁵ *e* is interposed between the mantle-support (in this instance the chimney-gallery) and the bracket or part fast to the bracket. The mantle *h* is supported usually from a loop formed on the upper end of a rod *h'*, which rod is secured in a socket *h*² in the chimney-gallery as by means of a clamp-screw, the head of which is shown at *h*³. In one form, as shown in Figs. 1 and 2, the spring *e* within the body of the air-shutter supports a washer *e*², from which rods *e*³, extending through holes in the upper part of the air-shutter, project upward and support a collar *e*⁴, on which the chimney-gallery is directly supported. The elastic cushion thus 80 takes the whole weight of the chimney-gallery, chimney, and other parts and provides a support sufficiently sensitive to prevent any shock or vibration whatever from extending beyond the bracket to the detriment of the 85 mantle. 90

The lower burner-tube *c*, which is rigidly secured to the support *a*, extends upward through the air-shutter and within the burner-tube *k*, that terminates in a cap *k'*, usually 100

- having a perforated top, above which the flame extends when the lamp is lighted and over which the lower end of the mantle *h* drops, as shown in Fig. 1 of the drawings. This burner-tube *k* has a free sliding movement up and down upon the tube *c*, limited in extent by the spring-cushion *e*. This upper section *k* of the burner-tube is sufficiently loose to enable the parts of the telescopic burner-tube 5 to move freely, so as to support the mantle and insulate it from vibrations and shocks.
- The modified form of my invention, as shown in Fig. 3, consists of a cushion in which the spring member *i* is mounted between two collars *i'* *i''*, the lower collar *i''* resting on top of the air-shutter and the collar *i'* underlying the bottom of the chimney-gallery, no part of this being arranged or located within the air-shutter. This form of cushion is easily adapted 10 to the present forms of burner and air-shutter without requiring any change in their structure.

I claim as my invention—

1. The combination in an incandescent gas-burner, of a spring-support constructed to carry the mantle and prevent undue vibration and shaking thereof, with a telescopic tubular connection for supplying gas without interfering with the action of the spring-support.
2. The combination in an incandescent burner, of a bracket or like support for the lamp as a whole, a telescopic burner-tube for supplying gas, a mantle-support, and a yielding cushion interposed between the fixed section and the movable section of the burner-tube, whereby gas is supplied within the mantle without interfering with the action of the spring-support.
3. In combination with a bracket or like support for a lamp having a fragile mantle over the flame, an air-shutter, a yielding cushion located in the shutter, and the man-

tle-support resting upon the yielding cushion, all substantially as described. 45

4. In combination with a bracket or like support for a lamp having a fragile mantle over the flame, an air-shutter, an elastic cushion located within the shutter, supports extending from the cushion upward through 50 the mantle, and the mantle-support mounted on the supports from the yielding cushion, all substantially as described.

5. In combination with a bracket or like support for a lamp having a fragile mantle 55 over the flame, an air-shutter, a spring located within the shutter, a collar borne on the spring, supports extending upward from the collar through the wall of the shutter, a collar secured to the upper part of the supports, 60 and a mantle-support borne on said collar, all substantially as described.

6. In combination with a bracket or like support for a lamp having a fragile mantle over the flame, an air-shutter, a yielding 65 cushion located in the shutter, a chimney-gallery supported on the yielding cushion, and a mantle-support secured to the chimney-gallery, all substantially as described.

7. In combination with a bracket or like support for a lamp having a fragile mantle over the flame, a tubular connection between the support and the burner of said lamp, a mantle-support, and a yielding cushion interposed between the lamp-support and the mantle-support. 75

8. In combination in an incandescent burner, of a spring-support constructed to support a mantle and prevent undue vibration or shaking thereof, with a tubular connection for supplying fluid without interfering with the action of the spring-support. 80

FRANK A. CORTIS.
